United States Patent Office

Des. 222,288

Patented Oct. 12, 1971

222,288

COASTER

Homer Gilliam, Jr., Box 937, Leesburg, Va. 22075

Filed July 24, 1970, Ser. No. 44,104

Term of patent 14 years

Int. Cl. D7—01

U.S. Cl. D44—10

Fig. 1.

Fig. 2.

Fig. 3.

FIG. 1 is a top plan view of a coaster embodying my new design;

FIG. 2 is an elevational view thereof; and

FIG. 3 is a sectional view along the line of 3—3 in FIG. 1.

I claim:

The ornamental design for a coaster, substantially as shown.
